UNITED STATES PATENT OFFICE.

MARTIN D. MILLER, OF SPRINGFIELD, MISSOURI, ASSIGNOR OF ONE-HALF
TO JOHN HECKART, JR., OF SAME PLACE.

LUBRICATOR.

SPECIFICATION forming part of Letters Patent No. 256,807, dated April 18, 1882.

Application filed February 21, 1882. (No model.)

To all whom it may concern:

Be it known that I, MARTIN D. MILLER, a citizen of the United States, resident at Springfield, in the county of Greene and State of Missouri, have invented a new and valuable Improvement in Lubricators; and I do hereby declare that the following is a full, clear, and exact description of the construction and operation of the same, reference being had to the annexed drawing, making a part of this specification, and to the letters and figures of reference marked thereon.

The figure of the drawing is a representation of a vertical sectional view of my oil-pump.

This invention has relation to lubricators; and it consists in the novel construction and arrangement of parts hereinafter fully described, and particularly pointed out in the claims.

In the accompanying drawing, the letter A designates the oil-reservoir, which is usually constructed with a cap-plate, B, base C, and cylinder-wall D, secured between the cap and base by means of bolts E. The base portion 25 of the reservoir extends downward, as indicated at F, and is recessed from below upward to form a piston-chamber, G, and above this chamber an oil chamber or cylinder, H, of relatively small diameter, into which oil flows 30 from the reservoir through a passage, a, and from which the oil flows through a passage, b, which is designed to be connected to the engine by means of suitable tubes or piping. At the lower end of the extension F of the base 35 C a connection is made with the steam-cylinder, near one end thereof, the cylinder being tapped for this purpose.

In the chamber G is located a piston, K, having an upward extension, c, whereby it is 40 connected to a piston, L, of smaller diameter, which works in the oil chamber or cylinder H, said piston L forming therefore the upper end of the piston K, but being usually made of soft metal, and connected thereto as indicated in 45 the drawing. A spring, N, is located in the chamber G, and is designed to exert a downward pressure on the piston when the steam-pressure is relieved by the exhaust. Steam being admitted from the cylinder at d actuates the piston K, forcing upward the smaller 50

oil end or piston, L, until it passes and closes the passage a from the oil-reservoir. The oil is thus forced through the passage b and its connecting-pipe to the engine. In the line of connection a check-valve of any ordinary construction is designed to be inserted, as indicated at P, the check-valve in this case being connected by a nipple immediately to the pump; but, if thought advisable, a check-valve may be constructed in the outlet oil-passage of the 60 pump.

Oil is fed into the reservoir at e, and the opening is provided with a cover, g, which may be pivoted on the end of one of the bolts E. Within the reservoir and near the cap is located a strainer, h, which is designed to insure that the oil in the reservoir shall be free from extraneous matter.

S indicates a regulating device controlling the upward movement of the piston, and consequently governing the oil-feed to the engine.

In the drawing, a regulating-screw is illustrated, passing through the cap-plate of the reservoir and through the base by a threaded aperture, k, into the oil-chamber. The lower 75 end of the screw-stem is made conical or conoidal, as indicated at n, and when the screw is set by means of its handle T the point n serves as a stop, preventing the upward movement of the piston beyond the point. As the 80 oil-piston L is made of soft metal, the tendency of this repeated stoppage is to spread the piston, and thereby compensate for wear. A jam-nut, p, located on the upper portion of the regulating-screw, serves to aid in fastening it 85 after the adjustment has been made for the feed.

Instead of using a regulating-screw, a cam may be employed, connected to a stirrup from the piston, extending downward; but the screw 90 is deemed preferable. Steam entering at d, as aforesaid, forces the piston upward and feeds the oil forward through the check-valve into the engine at any required point or points. When the steam is exhausting during the alternate movements of the piston in the steam-cylinder, the spring N reacting forces the piston downward in the oil-cylinder to its lower position below the passage a from the oil-reservoir, so that the oil-chamber again becomes 95 100

filled. In this manner the oil-forcing piston is alternately moved upward and downward, automatically feeding the oil forward to the engine. Preponderance of steam-pressure on the lower or larger piston-surface, K, operates to force the oil into steam-passages, although the pressure of steam against the oil may be to the square inch as great or greater, so that the action of the pump is positive.

Having described this invention, what I claim, and desire to secure by Letters Patent, is—

1. The lubricator having, in connection with the oil-cylinder and its communicating oil-reservoir, an oil-forcing piston and a screw regulating-stop, adjustable in said oil-cylinder, substantially as specified.
2. In a lubricator, the combination, with the oil-reservoir and its connected oil-cylinder, of

the oil-forcing piston, made larger at its steam end than its oil end, a spring, and an adjustable regulating device, governing the play of the oil-forcing piston, substantially as specified.

3. In a lubricator, the combination, with the oil-reservoir and its communicating oil-cylinder, the steam-chamber, and the oil-forcing piston, having a soft-metal oil end, of the spring, the screw regulating-stem extending into said oil-cylinder, and a check-valve, substantially as specified.

In testimony that I claim the above I have hereunto subscribed my name in the presence of two witnesses.

MARTIN D. MILLER.
